UNITED STATES PATENT OFFICE.

GARDNER H. PERKINS, OF CAZENOVIA, NEW YORK.

HAY-KNIFE.

SPECIFICATION forming part of Letters Patent No. 281,552, dated July 17, 1883.

Application filed June 11, 1883. (No model.)

To all whom it may concern:

Be it known that I, G. H. PERKINS, a citizen of the United States, residing at Cazenovia, in the county of Madison and State of New York, have invented certain new and useful Improvements in Hay-Knives; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of this invention, and is a front view. Fig. 2 is a side view. Fig. 3 is a vertical section, the top part of the handle being broken off. Fig. 4 is a detail showing the bevel on the cutting-plate.

This invention has relation to hay-knives; and it consists in the construction and novel arrangement of the square cutting-plate having four cutting-edges meeting in as many points and eight perforations circularly arranged around a central aperture, and the handle having a pivot connecting it to the center of the plate, and a movable pin-fastening, whereby the position of the plate or blade may be fixed after adjustment, all as hereinafter set forth.

In the accompanying drawings, the letter A designates a square plate of steel, having a central aperture, b, for the passage of the pivot-bolt c, whereby it is connected to the handle D. The plate is formed with four cutting-edges, e, meeting in as many points g, and has eight perforations, h, circularly and regularly arranged around the central or pivotal aperture, b, so that each perforation h is in line

between the center of the plate and one of its points or the middle of one of its straight edges e. The plate is therefore adjustable to provide a pointed cutting-blade or a square cutting-blade, the latter being especially adapted to cutting roots and the former for hay or turf. In order to secure the blade in position after adjustment, a screw or pin, k, is provided, which extends through the handle into one of the perforations of the blade. The handle is designed to be provided with a step, l, which is in such position with reference to the blade that the cutting-edges of the latter can be ground with facility.

This instrument is designed to serve many useful purposes, and can be made very strong and durable. It is advisable, in order to avoid too frequent sharpening, to keep two of its cutting-edges for hay, the other two being used for cutting turf, roots, &c.

Having described this invention, what I claim, and desire to secure by Letters Patent, is—

The hay-knife consisting of the square blade having four cutting-edges meeting in as many points and eight perforations circularly arranged around a central aperture, the handle having a pivot connecting it to the center of the blade, and a movable fastening adapted to engage one of the circular series of perforations to secure the blade in position, substantially as specified.

In testimony whereof I affix my signature in presence of two witnesses.

GARDNER H. PERKINS.
